UNITED STATES PATENT OFFICE.

WILLIAM METZROTH, OF SYRACUSE, NEW YORK.

TOOTH-BRUSH HOLDER.

1,167,833.

Specification of Letters Patent. Patented Jan. 11, 1916.

Application filed April 24, 1915. Serial No. 23,621.

To all whom it may concern:

Be it known that I, WILLIAM METZROTH, a citizen of the United States of America, residing at the city of Syracuse, county of 5 Onondaga, and State of New York, have invented certain new and useful Improvements in Tooth-Brush Holders, of which the following is a specification.

This invention relates to a holder for supporting a tooth brush and shielding the bristles thereof, the object of the invention being to provide such a device which may be conveniently supported and which may be removed from its support for the purpose of cleansing, and one which securely supports and shields the brush and admits of its ready removal and insertion, and which also affords the admission of a sufficient amount of air to permit the brush to readily dry.

In the drawings accompanying this invention one practicable embodiment of the invention is illustrated.

In such drawings, Figure 1 is a perspective or side elevation of the device supported by a clip from a wall and carrying a tooth brush. Fig. 2 is a sectional view of the device shown in Fig. 1. Fig. 3 is a top or plan view of Fig. 1, and Fig. 4 is a cross-section taken on a plane at about the line 4—4 of Fig. 2 looking down, the brush, however, being illustrated in plan.

The main holder portion 5 is preferably made of transparent material, such, for instance, as glass, and a material which is of a cleanly character and which is capable of ready cleansing and sterilization without deterioration.

For the purpose of permitting ready support and adjustment of the holder, its upper portion 6 is shown substantially cylindrical. This portion is shown in the grasp of the arms 7 of a clip which is shown secured by ordinary wood screws 8 to the board 9. The holder 5 is shown provided with a closed top 10 so that nothing may find access to the holder from this part. By this means the brush portion 11 of the tooth brush is securely guarded from dust and such contamination as a brush is exposed to in the usual places where such brushes are generally kept while in use. The lower portion of the holder 5 is provided with a shelf 12 for engaging the lowermost or rearmost row of bristles of the brush 11. This shelf is shown having at its edge an upturned bead 13 for

preventing accidental misplacement of the brush. The side 14 of the casing is shown flaring away from the main chamber of the casing and from the bead edge of the shelf 12 for affording a bottom opening 15 for the insertion and withdrawal of the brush and for the entrance of air to the brush.

In one aspect of the invention the casing is provided with a closed top and open bottom, such bottom, however, being provided with a support for engaging the brush.

When it is desired to insert the brush in the casing it will be passed through the opening 15, the handle of the brush assuming the dotted line position 16 in Fig. 2. After the brush has been inserted to a sufficient distance for the rearmost row of bristles to clear the bead 13, the brush is then moved to full line position 17, in such view, the brush handle just below the bristles occupying the space 18; the brush is then caused to descend until the bristles engage the support, in the illustration the shelf 12. The support or shelf is shown ending short of one side of the casing for affording space for the brush handle, and short of another side for affording an opening for the introduction and withdrawal of the brush.

The brush, after being inserted in the holder after use, readily dries, and is thoroughly shielded and well supported, and is removed by a reversal of the inserting movement.

When it is desired to remove the casing for cleansing it is merely drawn from the supporting clip and cleansed and returned to position. The upper portion of the case is preferably rotatably mounted between the arms 7 of the spring clip. The entrance opening may be either disposed as in the illustration directed toward the righthand side or it may be directed toward the front or toward the left-hand side, and may be changed from one position to another, as the preference and convenience of the user may dictate.

Although one form of the invention is shown in the drawings, it will be understood that this is illustrative of the invention, and that changes may be made within the scope of the claims without departing from the spirit of the invention.

What is claimed is:

1. A tooth brush holder, comprising a casing having a closed top, a brush sup-

port at the bottom, the side of the casing flaring away from the support for affording an opening adjacent the support for the introduction and withdrawal of the brush.

5. 2. A tooth brush holder, comprising an integrally formed casing having a closed top, a brush support at the bottom, the side of the casing flaring away from the support for affording an opening adjacent the support for the introduction and withdrawal of the brush.

3. A tooth brush holder, comprising a casing having a closed top, a brush support at the bottom formed as a shelf, the side of the casing flaring away from the support for affording an opening adjacent the support for the introduction and withdrawal of the brush.

15. 4. A tooth brush holder, comprising a

casing having a closed top, a brush support 20 at the bottom, formed as a shelf ending short of one side of the casing for affording space for the brush handle, and short of another side for affording an opening for the introduction and withdrawal of the brush. 25

5. A tooth brush holder, comprising a casing having a closed top, a brush support at the bottom formed as a shelf ending short of one side of the casing for affording space for the brush handle, and short of another 30 side for affording an opening for the introduction and withdrawal of the brush, the shelf adjacent the latter side being provided with a retaining bead.

In witness whereof, I have hereunto 35 signed my name.

WILLIAM METZROTH.
